UNITED STATES PATENT OFFICE.

THEODORE L. NEUMANN, OF DAYTON, OHIO, ASSIGNOR TO THE DAYTON PAPER NOVELTY COMPANY, A CORPORATION OF OHIO.

PAPER BOX FOR GOLF CLUBS AND THE LIKE.

Application filed December 3, 1925. Serial No. 72,907.

This invention relates to new and useful improvements in paper boxes for golf clubs and the like.

It is the principal object of my invention to provide for the reception of a set of golf clubs, preferably three in number, a paper box in which they may be shipped to, and attractively displayed in, a store and in which they may be easily delivered or 10 carried home by the customer.

It is another object of my invention to provide for the above purpose a paper box which may be economically made in large quantities from blanks colored on one side 15 only and whose principal parts may be folded outwardly to assemble it.

Other important and incidental objects will be brought out in the following specification and particularly set forth in the 20 subjoined claims.

In the accompanying drawings illustrating my invention, Figure 1 is a perspective view of the assembled box, showing the position of the golf clubs therein in dotted 25 lines. Figure 2 is a blank view of the body of the box, the folding lines being indicated by dotted lines and the severed portions by full lines. Figure 3 is a blank view of one of the ears for retaining the handles of 30 the clubs placed in the box adjacent the sides thereof. Figure 4 is a blank view of the member for holding the handle of the center club and positioning the heads of the two outer clubs. Figure 5 is an as- 35 sembled view of this member. Figure 6 is a sectional view taken on the line 6—6 of Figure 5. Figure 7 is a plan view of the body of the box when assembled. Figure 40 8 is a sectional view taken on the line 8—8 of Figure 7. Figure 9 is a sectional view of the box taken on the line 9—9 of Figure 7 to show the positioning member for the clubs. And Figure 10 is a sectional view taken on the line 10—10 of Figure 7.

45 Referring to the accompanying drawings for a detailed description of my invention, the numeral 1 designates a blank of cardboard or similar material which may be

colored on one side only, as on the side *a* in Figure 2.

The blank 1 is creased to form a central four-sided figure which provides the bottom 50 2 of the box. This figure has longitudinal sides designated by creases 3, 3 which regularly diverge from one end designated by 55 the crease 4 to the other end which is parallel to the first end and designated by the crease 5. (See Figure 2.)

Beyond the crease 4 the bottom section 60 2 of the box blank terminates in a tongue 6 which is transversely creased at the point 7 a short distance from the crease 4, and at the points 8, 9 and 10 near its free end, to permit the tongue to be easily folded outwardly as will be hereinafter described. 65 (See Figure 2.)

Beyond the crease 5 the bottom section 70 2 of the box blank terminates in a tongue 11 narrower than the tongue 6 but containing transverse creases 12, 13, 14 and 15 corresponding in position to the creases 7, 8, 9 and 10 respectively to permit it to be folded outwardly in a manner similar to the tongue 6. (See Figure 2.)

Along the creases 3, 3, sides 16, 16 are integral with the bottom section 2 of the box blank and are each divided by a longitudinal crease 17 parallel with its respective crease 3. The outer part of each side 16 has at each end an extension 18, the extension on one side being formed with a hook portion 19 that is adapted to enter a slit 20 in its companion section to fasten both extensions together when they are turned inwardly along the creases 21, 21.

The blank 1 may be assembled by folding its sides 16, 16 outwardly upon themselves along the longitudinal creases 17 to bring the surface *a*, which may be colored, to view within and without the box, after which the folded parts of the sides are glued together to reinforce them and to make it appear that they are colored on both sides. Thus a less expensive cardboard, such as that which is colored on one side only, may be used. 95 (See Figures 1, 2 and 9.)

After the sides 16, 16 are folded as above described, the tongue 11 is turned upwardly and the extensions 18, 18 at its end of the box are brought behind it and locked together by inserting the hook 19 of one extension into the slit 20 of the other. The tongue 11 is then turned outwardly and downwardly over and against the united extensions 18, 18, after which the extreme outer creased end of the tongue is tucked between said extensions and the outer portion of itself to form a strongly reinforced end for the box, with each side of said end forming a continuous surface, which may be colored, with the bottom section 2.

Formed in each side 16 of the box, near its narrow end and between the creases 3 and 17, is a transverse slit 22 to receive the shouldered end of an ear 23. Referring to Figure 3, each ear 23 is made up of two like sections having a central crease line about which they are turned against each other and glued together. To make it possible for these sections to bend without breaking, the grain of the paper of which they are composed runs the short way. The paper blank may also be colored on one side only, as on the side b in Figure 3, but the ear itself will appear to be colored on both sides when the two sections of which it is composed are folded against each other. As will be observed from Figure 3, the front portion of the ear is cut away to form shoulders 23^a, 23^b, so that the folded ear may be inserted within a slit 22 that is narrower than its shouldered end, whereby the latter will lock the ear in a position just above the bottom of the box to receive, through a hole 24 within it, the handle of a golf club. The ears 23, 23 are inserted in the slits 22 before the parts of the sides 16 of the box are folded against themselves, so that when these side parts are glued together, the ears may be firmly held between them.

To properly maintain the golf clubs, of which there are three, in the wider end of the box, there is provided a triangular positioning member 25 which will now be described. Referring to Figure 4, the member 25 is made from a blank of cardboard or similar material that may be colored on one side only as the side c in Figure 4, and shaped and creased as follows: The main part of this blank is composed of a central rectangular section 26 which terminates at one end, beyond a transverse crease 27, in an extension 28 having one inclined side. Beyond a transverse crease 29 at its other end, the central section 26 terminates in an extension 30 formed with a handle receiving hole 31. Beyond this hole the extension 30 has a transverse crease 32 to permit its outer end to be easily folded.

The central part 26 of the positioning member blank carries between its creases 27

and 29, inclined side wings 33 and 34 which are formed as shown in Figure 4. The side wings have middle transverse creases 35, 35 and longitudinal creases 36, 36 which extend outwardly from the ends of the crease 27 at equal acute angles to the creases 37, 37 respectively which define the sides of the main part 26. At its inner free corner the wing 33 has an extension 38 that is adapted to be turned outwardly along a crease 39. Between this extension 38 and the juncture of the crease 27 with the inner side of the wing 33, the latter is formed with an ear 40 which is divided by the crease 35 into a triangular inner part and a rectangular outer part. The side wing 34 is formed opposite the ear 40 with a similar ear 41. Beyond the ear 41 the side wing 34 has integral with its inner corner a flap 42 whose inner end forms an acute angle with said ear. By a transverse crease 43 the flap 42 is divided into two sections to make it outwardly foldable. (See Figure 4.)

When the positioning member blank is assembled, the apertured extension 30 of the main part 26 of it becomes the flat top of a pyramidal figure, after the ears 40 and 41 are brought toward each other under it. The main part 26 of the blank then becomes one inclined side, and the flap 42 the other inclined side, of the positioning member 25, the extension 38 of the side wing 33 being secured to the under side of the flap 42 by glue or other adhesive. One of the side wings 33 or 34 is then folded along the crease 36 under the apertured top 30 of the positioning member 25, after which the other side wing is folded against the first side wing, leaving the extension 28 on the main part 26, and the extension 44 on the flap 42 of the blank free. (See Figures 1, 4, 5 and 9.)

After the blank 25 has been assembled, it is placed in the end of the box 1, with its top 30 facing outwardly as shown in Figure 1. The extensions 28 and 42 are then folded over the inner surface of the tongue 6 of the box, after which the extensions 18, 18 of the sides 16, 16 respectively of the box are fastened together against the folded extensions 28 and 42 of the blank 25 by inserting the hook 19 of one extension into the slit 20 of the other. The tongue 6 is then folded outwardly along the crease 7 over the connected extensions 18, 18 of the box sides 16, 16. The tongue 6 is then bent along the creases 8, 9 and 10, or any others that may be formed in it, to permit its extreme outer end to be tucked under the connected extensions 18, 18 of the sides of the box, thus securely and neatly holding the positioning member 25 in the wide end of the latter. (See Figures 1 and 9.)

It is thus apparent that three golf clubs may be easily and compactly mounted in the box 1, as shown in dotted lines in Figure 1. 130

by fitting the handle of the middle club in the hole 31 in the positioning member 25, with its head resting against the middle portion of the narrow end of the box. On each 5 side of the middle club there is space for a golf club whose head rests against the inclined portion of the positioning member 25 and whose handle part projects through one of the ears 23 on its respective side of the 10 box. Holes 45 may be formed in the bottom 2 of the box to receive strings (not shown) by which the clubs may be tied firmly in the box if desired. By the positioning member 25, the ears 23 and the strings, if used, the 15 three clubs may be securely held in the box for attractive display in a store, and for shipment to, or delivery by, it after a suitable cover, such as that indicated in dotted lines in Figure 8, is applied.

20 Having described my invention, I claim:

1. A container comprising an elongated box to receive a number of clubs, and a pyramidal positioning member in one end of the box having a flat top portion formed 25 with a central hole to receive the handle of one club, and with downwardly inclined surfaces at the sides of said hole for engagement by the heads of two other clubs, one on each side of the middle club.

2. A container comprising an elongated paper box to receive a number of clubs, and having a tongue portion at one end thereof, a pyramidal positioning member in one end of the box formed with a central hole to 35 receive the handle of one club, and with surfaces at the sides of said hole for engagement by the heads of two other clubs, one on each side of the middle club, and extensions on said positioning member adapted 40 to be folded against the inner surface of said tongue member, after which the latter is adapted to be folded outwardly over, and then tucked under, said extensions, for the purpose specified.

45 3. A container comprising an elongated paper box to receive a number of clubs, a pyramidal positioning member in one end of said box to receive the handle of one club and to be engaged by the heads of two other clubs, one on each side of the middle club, and ears in the sides of said box to receive the handles of the two side clubs.

50 4. A container comprising an elongated paper box to receive a number of clubs, a positioning member in one end of said box to receive the handle of one club and to be engaged by the heads of the two other clubs, one on each side of the middle club, each side of the box being formed with a trans- 55 verse slit near the end thereof that is remote from the end containing the positioning member, and shouldered ears inserted in said slits and containing holes in their outer parts to receive the handles of the two side clubs.

5. A club-containing box comprising an elongated bottom section, and side sections adapted to be folded outwardly upon themselves and fastened together to form the sides of the box, the inner part of each side 70 containing a transverse slit, and ears containing holes in their outer ends projecting outwardly through said slits to receive the handles of clubs laid in said box, the inner portions of said ears being firmly held between the side sections when the latter have been folded upon themselves and fastened together.

6. A club-containing box having an elongated bottom section, and side sections 80 adapted to be folded outwardly upon themselves and fastened together to form the sides of the box, the inner part of each side containing a transverse slit, and ears projecting from said slits, each ear comprising 85 a blank of two equal sections with the grain running the short way and a transverse crease between them, each ear section containing a handle-receiving hole near the crease, said ear sections adapted to be 90 folded upon themselves around the crease, and fastened together, to bring said holes into registry, and thereafter adapted to be projected through the slits from the inside to bring said holes into position above the 95 bottom of the box to receive the handles of clubs laid therein.

7. A container comprising an elongated paper box to receive a number of clubs, and having a tongue portion at one end thereof, 100 side sections for said box having extensions parallel with said tongue portions, a club positioning member adapted to be placed in the end of the box having said tongue portion, and extensions on said positioning 105 member adapted to be folded against the inner surface of said tongue portion and connected together, after which the extensions on the box sides are adapted to be folded toward each other against the connected extensions on the positioning member, whereupon the tongue portion is adapted to be folded outwardly over, and then tucked under, said overlapping extensions of the box and the positioning member to 110 hold the latter firmly in the box end for the purpose specified.

8. In a paper box for golf clubs, a positioning member for said clubs adapted to be inserted in one end thereof, and comprising 115 a blank having a central part, one end of which contains a hole to receive the handle of a club, an extension on said central part, a side wing on each side of the central part, ears carried by said side wings near the 120 apertured portion of said central part of said blank, a flap carried by one side wing adapted, with the portion of the central part of the blank beyond said hole, to form surfaces which incline downwardly, one on each 125 130

side of said hole, to act as backing members for the heads of the clubs laid in the box, one on each side of the middle club whose handle said hole receives, and an extension 5 on one side wing adapted to be secured to the under surface of the flap on the other side wing to securely maintain said positioning member in its assembled state. In testimony whereof I have hereunto set my hand this 30th day of November, 1925.

THEODORE L. NEUMANN.
